UNITED STATES PATENT OFFICE.

BERTRAND B. KAHN, OF CINCINNATI, OHIO, ASSIGNOR TO THE ESTATE STOVE COMPANY, OF HAMILTON, OHIO.

HEATER.

1,337,708.

Specification of Letters Patent. Patented Apr. 20, 1920.

Application filed December 23, 1918. Serial No. 267,968.

To all whom it may concern:

Be it known that I, BERTRAND B. KAHN, a citizen of the United States, residing at Cincinnati, Hamilton county, Ohio, have invented certain new and useful Improvements in Heaters, of which the following is a specification.

This invention pertains to heaters designed for the employment of either gaseous or solid fuel and the improvements will be readily understood from the following description taken in connection with the accompanying drawing in which:—

Figure 1 is a front elevation illustrating an embodiment of my improvements:

Fig. 2 a rear elevation of the same:

Fig. 3 a vertical section in the plane of line *c*—*c* of Figs. 1, 2, 4, 5 and 6:

Fig. 4, a plan:

Fig. 5 a horizontal section in the plane of line *b*—*b* of Fig. 3:

Fig. 6 a horizontal section in the plane of line *a*—*a* of Fig. 3; and

Fig. 7 an elevation of a portion of one of the walls of the fire-pot. In the drawing:—

1, indicates the front wall of the body of the heater, which is generally rectangular in horizontal section:

2, the back wall of the same:

3, the fire-door:

4, the ash-pit door:

5, the fire-pot disposed within the body of the heater below the level of the fire-door and above the level of the ash-pit door, and formed of four separable walls, the rear and front walls being provided with ports 8:

6, a pair of straight burner pipes extending sidewise through the body of the heater outside of and at the base of the front and rear walls of the fire-pot, these burner-pipes having jet holes adapted to jet into the fire-pot through the ports in the bases of its front and rear walls:

7, the grate, disposed at the base of the fire-pot:

8, the ports previously referred to as being formed in the bases of the front and rear walls of the fire-pot, these ports being opposite the jet holes in the burner-pipes:

9, the ash-pit, below the grate:

10, the smoke outlet for the products of combustion, this smoke outlet being located at the rear of the top of the heater:

11, a wall extending from side to side of

the body of the heater, inwardly of its back wall, this wall being located exterior to but against the rear wall of the fire-pot, and extending from the base of the stove-body to a point below the level of the smoke outlet:

12, a fresh air flue open at its base, and formed between wall 11 and the back wall of the heater, this flue extending entirely from side to side of the body of the heater and extending from the base of the heater and having its roof below the smoke outlet 10 from the heater, which roof extends entirely across the stove from side to side:

13, a hot air flue open at the top of the heater and joining the front upper portion of flue 12:

14, a perforated cover for flue 13:

15, passages at each side of flue 13 placing the fire-pot in communication with the smoke outlet 10 as seen in Figs. 3 and 6:

16, the space to the rear of flue 13, placing the smoke outlet in communication with the passages 15 at the sides of flue 13:

17, a gas supply-pipe extending fore and aft at one side of the exterior of the heater:

18, mixers at the ends of the burner-pipe, jetted into by suitable controlling nozzles connected with the gas supply-pipe:

19, holes through the back wall 12, above the level of the burner-pipes: and

20, supporting bars disposed at the inside of each side of the heater and having their ends resting on lugs on wall 11 and the front wall of the heater, these bars being disposed below the base of the fire-pot.

The bars 20 are separably supported in the body of the heater and the front and rear walls of the fire-pot rest upon them, the two burner-pipes resting on seats formed on the ends of the bars exterior to the front and rear walls of the fire-pot. The grate, which may be horizontally pivoted, fits endwise between these bars and its fore and aft dimensions are such that it may be tilted in dumping the contents of the fire-pot.

In burning solid fuel, the fuel is placed in the fire-pot, through the fire-door, and the products of combustion find their way to the smoke outlet through passages 15 and space 16. Fresh air enters the base of flue 12 and discharges through perforations of cover 14. This air serves, in great measure, to insulate the back wall 2 of the heater and prevent much of the radiation 110

therefrom. Wall 11 is dished rearwardly at the rear burner-pipe, thus narrowing flue 12, under which circumstances holes 19 become useful in admitting air to the back flue in spite of the restrictions produced by the dishing which has been mentioned. The presence of air flue 12, extending as it does from the base of the heater to the base of space 16, which is well above the level of the main combustion chamber of the heater, 10 serves in generally insulating the back of the heater without interfering with radiation from its sides and front.

When gaseous fuel is to be used, the firepot is to be filled with lumps of refractory material, which are heated by the jets of gas issuing among them from the jet holes in the burner pipes, these jets entering the fire-pot through the ports 8. The products of combustion leaving the fire-pot reach the smoke outlet by the passages 15 and space 16, the air flue 12 serving, as before, to insulate the back of the heater, the radiation being confined mainly to its front and side walls, 25 the air passing through this flue discharging at perforations 14 and receiving heat through wall 11 and the surrounding walls of flue 13.

I claim:—

30 1. The combination with the front, side, and back walls of a heater having an upper smoke outlet, of an inner transverse wall extending the width of the heater structure and spaced from the back wall to form a 35 fresh air flue open at the bottom of the heater, an upper central hot air flue forming

a continuation of said fresh air flue, and a rear smoke chamber formed in the heater above said transverse wall and communicating with the interior of the heater around 40 said hot air flue, a firepot having its top joining said front, side, and transverse walls and formed with lower ports at the front and rear, a fire door, a grate, and burner pipes, having jet holes, between the heater 45 front and fire pot and between the transverse wall and firepot adjacent said ports.

2. The combination with the front, side, and back walls of a heater having an upper smoke outlet, of an inner transverse wall 50 extending the width of the heater structure and spaced from the back wall to form a fresh air flue open at the bottom of the heater, an upper central hot air flue forming a continuation of said fresh air flue, and 55 a rear smoke chamber formed in the heater above said transverse wall and communicating with the interior of the heater around said hot air flue, opposed lugs on said front and transverse walls and supporting bars 60 resting on said lugs, a fire pot having its top engaging the front and transverse walls and resting on said bars, burner pipes on said bars between the front wall and fire pot and transverse wall and firepot, a grate at the 65 base of the firepot, and said burner pipes adapted to discharge through ports in the fire pot.

BERTRAND B. KAHN.
